M. P. HOLMES

SAFETY APPLIANCE FOR MINING MACHINES

Filed June 11, 1921

UNITED STATES PATENT OFFICE.

MORRIS P. HOLMES, OF CLAREMONT, NEW HAMPSHIRE, ASSIGNOR TO SULLIVAN MACHINERY COMPANY, A CORPORATION OF MASSACHUSETTS.

SAFETY APPLIANCE FOR MINING MACHINES.

Application filed June 11, 1921. Serial No. 476,756.

To all whom it may concern:

Be it known that I, MORRIS P. HOLMES, a citizen of the United States, residing at Claremont, in the county of Sullivan and State of New Hampshire, have invented certain new and useful Improvements in Safety Appliances for Mining Machines, of which the following is a full, clear, and exact specification.

10 This invention relates to safety appliances for bodily movable machines.

The invention has for its general object to provide means for automatically stopping the operation of such a machine in the event of accidental movement thereof in a direction other than that in which it is meant to travel. Another object of the invention is to provide mechanism of the character referred to which will not only stop the operation of the machine but will also arrest the bodily movement thereof. A more particular object of the invention is to provide a safety appliance for mining machines of the type employing a feed chain or cable for moving the machine bodily along the mine face and instrumentalities for cutting a kerf in said face as the machine is so moved, said appliance being of such a character that, should the feed chain or cable break 30 while the machine is travelling up an incline, rearward movement of said machine down said incline will be immediately arrested, and the operation of the cutting instrumentalities instantly stopped in order 35 to prevent injury to the machine or to the operator.

The foregoing and other objects of invention, together with means whereby the same may be carried into effect, will best be understood from the following description of one form or embodiment thereof illustrated in the accompanying drawings, in which:

Fig. 1 is a plan view of a mining machine 45 having the invention applied thereto.

Fig. 2 is an enlarged vertical section of the rear of the machine taken substantially on the line 2—2 of Fig. 1.

Fig. 3 is an enlarged plan view of the 50 rear end of the machine with the top cover plate and cutter bar removed.

Fig. 4 is a detail section on the line 4—4 of Fig. 2.

Fig. 5 is a detail view of the clutch controlling mechanism.

The mining machine shown in the drawings is of the longwall type having a frame or casing 1 and a cutter bar 2. The latter carries the usual cutter chain 3 provided with cutter bits 4 and is pivotally connected to one end of the frame and held as desired either in opposite lateral positions or in a longitudinal position by a removable pin 5 cooperating with registering recesses 6 in the frame and bar. A suitable feed operating member 7 is also rotatably mounted at the opposite end of the frame and is adapted to cooperate with a flexible feeding member of any suitable form, herein shown as a feed chain 8 which passes about 60 suitably disposed guide sprockets 9. As in a well known construction, the feed operating member 7 is driven from a motor 10 within the casing through usual connections, not shown. The motor shaft 11 carries a bevel pinion 12 which meshes with a bevel gear 13 fast upon a sleeve 14 which carries a spur pinion 15 meshing with a spur gear 16 adapted to be connected, through suitable clutch devices 17, with a sprocket 18 for actuating the cutter chain 3. 70

The parts thus far referred to are of a construction and arrangement well known in the art and require no further description in detail. In the use of a machine of the type shown, the cutter bar 2 is swung in under the mine face in any suitable manner, as for instance by connecting the feed chain to projections 19 on the bar, and then simultaneously operating the cutter chain 3 and feed operating member 7. The feed chain 8 is then extended along the face and anchored at its ends, so that when the feed operating member 7 and cutter chain 3 are again simultaneously operated, the machine will 80 move bodily along the feed chain and the face, and will occupy the position illustrated in Fig. 1 during its traversing cutting operation.

As is also usual in machines of this type, the clutch devices 17 are operated by arms 20 on a rock shaft 21 journaled in a bracket 22 secured at a suitable point to the main frame 1, said clutch devices comprising pins carried by a ring 17^a rotatably cooperating with upstanding arms 17^b connected with the arms 20 (Fig. 5). In accordance with the present invention, means are provided for automatically operating the clutch devices 17 to disconnect the sprocket 18 from 90

the gear 16 and stop the operation of the cutter chain 3 should the machine for any reason, as for example breakage of the feed chain 8 when the machine is operating on a pitch or incline, start to move backwardly, said means preferably also operating to arrest such bodily movement of the machine. Such means may obviously assume various forms, but in the embodiment of the invention illustrated the following mechanism is provided.

The machine frame 1 is formed at a suitable point adjacent its rear end, and preferably at or near the top thereof, with a short, longitudinally disposed, under-cut guide-way 23 in which is mounted a slide 24. Pivoted at 25 to the slide 24 is a sprag 26 which extends upwardly and rearwardly from the rear end of the machine and is formed with a pointed end adapted to engage with the roof of a gallery in which the machine is operated and to follow the surface of said roof as the machine is moved forwardly. The sprag 26 is preferably connected with the slide 24 by a suitable yielding connection, herein in the form of a relatively light coiled spring 27 operatively connected between a collar 28 substantially midway between the ends of the sprag and a point at the top of an upright portion 29 of the slide 24. As a result of this spring connection, it will be observed that the sprag is normally held in the upwardly and rearwardly inclined position shown in Fig. 2. Secured at its rear end to the upright portion 29 of the slide 24 is a horizontal rod 30 guided for longitudinal movement in the machine frame and connected by a link 31 to an arm 32 on the rock shaft 20, whereby, when said rod 30 is moved forwardly, said rock shaft will be operated to disconnect the clutch devices 17 and stop the operation of the cutter chain 3.

In order to start the cutter chain 3, the slide 24 is manually moved into its rearmost position as shown in Fig. 2, thereby drawing the rod 30 rearwardly and operating the rock shaft 21 to engage the clutch devices 17. During the normal forward travel of the machine, the sprag 26 will tend to occupy the position shown in Fig. 2, its upper end following the roof surface, and the spring 27 holding the same in engagement with the roof, the slight rearward drag of said sprag tending to maintain the slide 24 in its rearmost position and the cutter chain clutch engaged. Should, however, the machine start to move bodily rearwardly for any reason, as, for example, upon breakage of the feed chain when the machine is travelling up an incline, such rearward movement will tend to drive the upper end of the sprag into the roof, thereby arresting such rearward movement. At the same time, the reaction of the lower or forward

end of the sprag upon the slide 24 will move said slide forwardly in the guide-way 23, carrying with it the rod 30, such forward movement of the rod acting through the link 31 to rock the shaft 21 and operate the clutch devices 17 to disconnect the sprocket 18 from the gear 16, thereby immediately stopping the operation of the cutter chain.

From the foregoing it will be seen that the invention provides means whereby both the operation and the bodily movement of a machine may be automatically arrested upon incipient movement thereof in a direction opposite from that in which it is intended to move. It will be noted, however, that whenever it is desired to permit a free rearward movement of the machine, the sprag may be readily rendered inoperative by disconnecting the spring 27, said sprag being preferably of such a length and so mounted upon the machine frame as to fall idly to the rear of the machine without engaging the bottom over which the machine is moved.

While I have herein specifically shown and described one embodiment which my invention may assume in practice, it will be understood that the particular construction and arrangement described and shown have been chosen for illustrative purposes merely, and that the invention may be otherwise embodied and practiced without departing from its spirit or the scope of the claims hereunto appended.

What I claim as new and desire to secure by Letters Patent is:—

1. The combination with a bodily movable machine, of means including a pivoted element engageable with an extraneous abutment carried by said machine for automatically discontinuing the operation thereof only upon bodily movement thereof in one direction.

2. The combination with a bodily movable machine slidable on its own bottom, of means including a yieldable member engageable with an extraneous abutment carried by said machine for automatically discontinuing the operation thereof upon only bodily movement thereof in one direction.

3. The combination with a bodily movable machine having moving parts, of means engageable with an extraneous abutment automatically operative only upon bodily rearward movement of said machine to stop the operation of said parts.

4. The combination with a bodily movable machine comprising an actuator, a driven member, and a clutch connecting said actuator and member, of means carried by said machine and engageable with an extraneous abutment for automatically disengaging said clutch only upon bodily rearward movement of said machine.

5. The combination with a bodily movable machine, cutting mechanism carried by said

- machine, and means engageable with an extraneous abutment for automatically discontinuing the operation of said cutting mechanism only upon bodily movement of 5 said machine in one direction.
6. In a mining machine, the combination with a cutter chain, a motor, and driving connections including a clutch between said chain and motor, of means automatically operative upon bodily rearward movement of said machine to disengage said clutch and stop said cutter chain.
7. The combination with a bodily movable machine, of means carried by said machine and adapted to engage a fixed extraneous object adjacent the path of movement of said machine for automatically discontinuing the operation of said machine only upon bodily movement thereof in one direction.
8. In a mining machine, the combination with a motor, a cutter chain, and driving connections including a clutch between said motor and chain, of means carried by said machine for engaging a gallery roof and adapted upon rearward movement of said machine to disengage said clutch.
9. The combination with a bodily movable machine, of a slide guided for movement on said machine, means pivotally mounted on said slide for engaging a fixed extraneous object adjacent the path of movement of said machine, and means operated by said slide for discontinuing the operation of said machine.
10. The combination with a bodily movable machine comprising an actuator, moving parts operated thereby, and a clutch connecting said actuator and parts, of a slide guided for movement on said machine, means carried by said slide for engaging a fixed extraneous object adjacent the path of movement of said machine, and means including a pivoted shipping member operatively connected with said slide for operating said clutch.
11. The combination with a bodily movable machine slidable on a mine bottom, of means constantly engageable with a mine roof carried by said machine for automatically arresting movement of said machine only in one direction and substantially simultaneously discontinuing the operation thereof.
12. In a mining machine, the combination with a motor, a cutter chain, and driving connections including a clutch between said motor and cutter chain, of a slide guided for movement on said machine, a sprag pivoted to said slide, a rod connected to said slide, a rock shaft for operating said clutch, an arm on said rock shaft, and a link connecting said rod and arm.
13. In a mining machine, feeding means, cutting means, and controlling means for
14. In a mining machine, feeding means, cutting means, and controlling means for said cutting means including a pivoted sprag engageable with a gallery controlled by the failure of said feeding means to operate.
15. In a safety device for a mining machine, feeding means, cutting mechanism, actuating means therefor, and automatic means to disconnect said cutting mechanism from said actuating means only upon failure of said feeding means to operate.
16. In a mining machine, feeding mechanism, cutting mechanism, driving means therefor, and automatic means adapted to engage a stationary abutment and controlled only by the failure of said feeding mechanism to operate to disconnect said cutting mechanism from said driving means.
17. In a mining machine, feeding mechanism, cutting mechanism, driving means therefor, and means controlled by the failure of the feeding mechanism to operate and adapted to engage a mine roof and automatically disconnect said cutting mechanism from said driving means.
18. In combination with a mining machine, feeding means therefor, cutting mechanism, driving means therefor, a clutch interposed between said driving means and said cutting mechanism, and automatic means controlled by the failure of said feeding means to operate and operating to disconnect said clutch.
19. In a mining machine, flexible feeding means, cutting means, driving means therefor, and automatic means carried by the machine and engageable with a mine roof operative upon failure of said feeding means to disconnect the cutting means from the driving means.
20. In a mining machine adapted to slide upon a mine bottom, the combination with a cutter chain, a motor, driving connections including a clutch between said cutter chain and motor, and means automatically operative upon bodily rearward movement of said machine to disengage said clutch to stop said cutter chain.
21. The combination with a machine having bodily movement in a certain direction during operation, of means carried by said machine for automatically discontinuing operation thereof operative only upon movement of said machine in an opposite direction at any point of said machine movement during operation.
22. The combination with a machine having bodily movement in a certain direction during operation comprising an actuator, a driven member, and a clutch connecting said actuator and member, of means carried by

said machine for automatically discontinuing operation thereof operative only upon movement of said machine in an opposite direction at any point of said machine movement during operation for automatically disengaging said clutch.

23. The combination with a machine having bodily movement in a certain direction during operation, of means carried by said machine for automatically discontinuing the operation thereof only upon a predetermined movement in an opposite direction at any point of said machine movement during operation, said predetermined movement being of less magnitude than the distance of machine movement during operation.

24. The combination with a machine bodily movable in a certain direction during operation, of means carried by said machine for automatically discontinuing the operation thereof, said means receiving its initial movement from said machine only in an opposite direction at any point of said machine movement during operation.

25. 25. In combination, a mining machine, feeding means therefor including a flexible member, cutting mechanism, driving means

therefor, and automatic means controlled by the failure of said flexible feeding member and operating to disconnect said cutting mechanism from said driving means.

26. In a mining machine adapted to slide on its own bottom on the mine bottom relative to a flexible feeding member during operation, means for automatically discontinuing the operation thereof when said flexible feeding member fails to operate.

27. The combination with a machine bodily movable within certain limits during operation, of means carried by said machine for automatically discontinuing the operation thereof, said means being only operative upon movement of said machine in a reverse direction at any point between its limits of movement.

28. The combination with a bodily movable machine provided with feeding and cutting mechanism and driving means therefor, of means automatically operative upon movement of said machine in one direction for discontinuing operation thereof while said driving means constantly operates.

In testimony whereof I affix my signature.
MORRIS P. HOLMES.
